UNITED STATES PATENT OFFICE.

LLOYD E. GOODYEAR, OF CEDAR RAPIDS, IOWA.

LOOSE-LEAF BINDER.

1,415,834.

Specification of Letters Patent.

Patented May 9, 1922.

Application filed December 16, 1918. Serial No. 267,071.

To all whom it may concern:

Be it known that I, LLOYD E. GOODYEAR, a citizen of the United States, residing at Cedar Rapids, in the county of Linn and

5 State of Iowa, have invented certain new and useful Improvements in Loose-Leaf Binders; and I do hereby declare the following to be a full, clear, and exact description of the invention, such as will enable others 10 skilled in the art to which it appertains to make and use the same.

This invention relates to loose-leaf binders, the principal object of the invention being to provide a simple, inexpensive and 15 convenient holder for loose leaves, from which they may be easily and quickly detached, and when attached, permitting them to be turned readily, and to lie flat in either position.

20 In the accompanying drawing, forming a part of this specification—

Figure 1 is a plan view of my improved binder.

Figure 2 is an enlarged section on the line 25 2—2 of Figure 1.

Figure 3 is an enlarged section on the line 3—3 of Figure 1.

In the drawing, the numeral 10 denotes a suitable support for the leaf-holder, a tablet 30 or book-cover for example. The leaf-holder is a double-pronged stirrup 11 formed of a single piece of wire. The straight body portion thereof, 12 is pivotally attached to the support, so as to rock back and forth a 35 limited distance. At each end is an upturned arch 13 formed at right angles to the body or shaft of the holder. A simple mounting of the holder is shown in Fig. 1, being sheet metal plates 14 riveted to the 40 supporting cover or tablet, and having each an eye 15 to receive the shaft of the leaf-holder. The same plate is also pierced at 16 to receive the free end of the arch, and one or both of such arch-ends is barbed at 17 to 45 engage the under side of the plate when in holding position. In the case of a comparatively short and stiff holder, the barbing of one prong is sufficient, but for a long and light holder, whose shaft would be more 50 liable to twist, both prongs are barbed, as shown in Fig. 3. In this case the barbs are oppositely disposed, as shown, so that the spring of the holder shaft tends to hold them in engagement. The holes engaged by 55 the barbed prongs should be slotted or large enough to allow for the release of the prongs,

which is effected by slightly twisting one of the arches to disengage its barb, lifting it slightly, and sliding the holder endwise in its bearings to release the other prong. 60 When but one prong is barbed the twisting and lifting motions are all that are required, and the holes in the catch-plates 14 need be but slightly larger than the diameter of the prongs. Below these catch-plate holes are 65 holes 18 in the tablet, and to prevent the prongs from passing through too far the holes are closed on the outer sides by sheet-metal plates 19.

It will be obvious, of course, that spring 70 shafts 12 of different lengths may be used interchangeably with the mounting plates 14, thus permitting standardization of the mounting plates and adapting the binders to sheets of different width, merely by spacing the mounting plates when securing the same to the binder covers according to the width of the sheets to be bound therein and using spring shafts 12 of suitable lengths according to the spacing of the mounting 75 plates.

For leaves already perforated the prong-ends may be blunt, as shown in Fig. 2.

Having thus described my invention, I claim:

1. In a loose-leaf binder, a supporting tablet, a pair of catch plates attached thereto, and forming bearings for the leaf holder and a leaf-holder comprising a spring shaft having a pair of terminal arches whose free 90 ends are oppositely barbed for engagement with the catch-plates, the arches being released by twisting one of them to spring the shaft and disengage the arch, and sliding the shaft to disengage the other prong. 95

2. In a loose leaf binder, a supporting tablet, catch plates forming bearings secured to the tablet, and a leaf holder comprising a spring shaft mounted in the bearings and provided with a pair of terminal arches whose free ends are adapted to releasably engage the catch plates, the arches being released by twisting one of them to spring the shaft and disengage the arch and sliding the shaft to disengage the other 105 prong.

In testimony whereof I affix my signature in presence of two witnesses.

LLOYD E. GOODYEAR.

Witnesses:

A. T. COOPER,
J. M. ST. JOHN.
